UNITED STATES PATENT OFFICE.

CHARLES A. CORNIBERT, OF WOODSIDE, NEW YORK.

DESIGN FOR A CLOCK-FACE.

SPECIFICATION forming part of Design No. 26,486, dated January 5, 1897.

Application filed December 1, 1896. Serial No. 614,136. Term of patent 3½ years.

To all whom it may concern:

Be it known that I, CHARLES A. CORNIBERT, residing at Woodside, in the county of Queens and State of New York, have invented and produced a new and original Design for a Clock-Face, of which the following is a specification, reference being had to the accompanying drawings, forming a part thereof, in which—

Figure 1 is a front elevation of the clock-face embodying the features of my design, and Fig. 2 is a transverse section taken on the line 2 2 of Fig. 1.

The design consists in shells produced upon a tray in such order as to correspond to the

arrangement of the numerals upon a watch or 15 clock face. Each shell carries a numeral representing an hour of time, the said numerals being arranged to read from "1" to "12," inclusive. A knife and a fork appear as the hands of the clock-face. 20

I claim—

The design for a clock-face, substantially as herein shown and described.

CHARLES A. CORNIBERT.
